UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK.

RAILWAY-SWITCH-SELECTOR-OPERATING MEANS.

Application filed January 12, 1927. Serial No. 160,679.

This invention relates in general to the operation of track switches for railways, and has more particular reference to a combined switch operating and switch operator selecting means.

In the operation of track switches it is customary to throw the switches either by hand or by means of power operated machines, such as electrically operated switch machines for example, and under certain circumstances it is more desirable to operate the switch by hand, while under other circumstances it is more desirable that the switch be operated by machine. The various conditions and considerations under which the two stated methods of operation of a switch will be more desirable, have been set forth at considerable length in the introductory portion of copending application Ser. No. 155,484 filed December 17, 1926, in the name of Winthrop K. Howe and accordingly it is thought unnecessary to set this matter forth at length in the present specification.

With the above and other considerations in mind, it is proposed in accordance with this invention to provide a combined hand operated switch stand and switch operator selector in a single casing.

Further objects of the invention are, to simplify the structure, decrease the cost of production, and increase the efficiency and length of life, of devices of this character.

Further objects, purposes, and characteristic features of the present invention will appear as the description progresses, reference being had to the accompanying drawings, showing, solely by way of example, one form of the invention.

In the case of application Ser. No. 155,484, the hand operated switch stand is in a casing separate from that of the selector and the switch machine, and with such an arrangement it is at times difficult to obtain the necessary accuracy of relation between the hand throw movement and the other parts.

In the drawings:—

Fig. 1 is a plan view of a device constructed in accordance with this invention, parts being shown in section;

Fig. 2 is a sectional view on the line 2—2 of Fig. 1, viewed in the direction of the arrows; and

Fig. 3 is a schematic plan view of the de-

vice in question, together with its various associated parts on a trackway.

Referring to the drawings, the device comprises a casing 1 having a hinged cover 2 supplied with a hasp 3 for holding it in closed position. This casing is positioned, in the form shown in Fig. 3, to one side of track rails 4, constituting a trackway, while on the opposite side of the trackway is a switch machine 5 of any usual or suitable form, the one shown being an electrically operated machine controllable locally, or at a distance, as desired.

A power operated rod 6 connects the switch machine to a rod 7 which is slidably receivable in the casing 1, while a switch throw rod 8 is connected to a switch rod 9 which is likewise slidably receivable in this casing.

As best seen in Fig. 1, a hand operated rod 10 is slidably positioned in the casing 1, the three rods 7, 9, and 10, connected respectively to the switch machine, the track switch 11, and to a hand operating lever 12, are positioned to lie adjacent each other in the casing.

The hand operating lever 12, carrying a usual weight 13 at its end, operates a crank 14, through bevel gears 15 and 16, rocking of the crank 14 reciprocating the end 17 of a rod 18 connected to a crank by means of a pin 19. The end 17 of rod 18 is connected by a pin 20 to the hand operated rod 10, so that rocking of the lever 12 operates to reciprocate the rod 10 within the casing 1.

The rods 7, 9, and 10 are supplied with notches 21, 22 and 23, respectively, so positioned that they can be brought into registry with each other when the rods in question are properly positioned. In order to couple up the switch rod 9 with either one of the rods 7 or 10, there is a coupling finger 24 depending from a hub 25 which is slidably but non-rotatably carried on a squared shaft 26 mounted to rotate in the casing 1.

The squared shaft 26 carries an operating member 27 having spaced outstanding ears 28 thereon as best shown in Fig. 2 and arranged substantially 180° apart. The squared shaft 26 is operated through the member 27 by means of an inwardly projecting lug 29 carried on a cam 30 fixed to a stub shaft 31 to which is keyed a collar 32 having an operating rod 33 connected thereto, with a weight 34 at the end of the rod.

The operating rod 33 is held in either of its two extreme positions by means of latch members 35.

Bearing against the periphery of the cam 30 is an arm 36 having a sleeve 37 pinned to a shaft 38, the shaft 38 having pinned thereto a contact carrier 39 biased in an upward direction, by a spring 40 against an adjustable stop 41 carried by a lug 42 on the casing 1. The shaft 38 is pivoted in a bracket 43 bolted to the casing 1 and having a shelf 44 to which are connected resilient contact fingers 45 and 46 carrying contacts 45' and 46' respectively. The arrangement of contacts and contact block, just described, is substantially the same as that shown in the above referred to pending application No. 155,484, and hence a more detailed description is deemed unnecessary.

Connected to the rod 7 which is operated by the switch machine, is a stop member 47 arranged to butt against an adjustable stop screw 48, while the end of the rod 7 butts against an adjustable stop screw 49. This stop arrangement is used to take up the slack and spring which necessarily exists in a connecting rod of the length of rods 6 and 7, and the stop screws 48 and 49 are adjusted to agree with the stroke of the switch machine. This arrangement prevents the spring in the rods from moving the rod 7 after the switch machine has completed its stroke, and the advantage of this will be apparent after the operation of the device is set forth.

The various parts of the device are shown in the drawings in position for operation of the switch points 11 by the switch machine 5, the coupling finger 24, as seen in Fig. 2, engaging in the notches in the rods 7 and 9 to thereby connect the switch machine with the switch rod 7. In the position referred to the arm 36 is bearing against the lower portion of the cam 30 and the contacts 45' 46' are closed and these contacts are included in the circuit which energizes the switch machine 5. It will be noted in Fig. 1 that several sets of contacts have been shown, and these other contacts can be used for any desired purpose, such as the operation of wayside signals, for resetting purposes, and the like.

Assuming now that it is desired to operate switch points by means of the hand operated lever, the selector lever 33 is moved from the position shown in Fig. 1 towards its opposite extreme position. Immediately on movement of the lever 33 the high part of the cam 30 raises the arm 36 to thereby lower the member 39 against the tension of spring 40 to thus separate contact 46' from contact 45' and thereby cut off the supply of energy to the switch machine 5. As the movement of the lever 33 continues, the lug 29 rotates 65 counter-clockwise as viewed in Fig. 2, but

has no operative effect on the operating member 27 until the lever 33 has moved almost 180°. As the lever 33 completes its movement, the lug 29 presses against the opposite shoulder 28 on operating member 27 to thereby rock the squared rod 26 and with it the coupling finger 24, to cause it to assume a position in which it engages in the grooves of the rods 9 and 10 to thus couple the hand operated rod 10 with the switch throw rod 9. The switch points 11 can now be thrown by hand in the usual manner by means of the lever 12.

In the above description of the operation of this device it should be noted that the initial movement of the selector lever 33 either makes or breaks the circuit including the contacts 45' 46', while it is only the final movement of this lever which causes operation of the coupling finger 24 to reverse the coupling of the switch rod 9 from the switch machine operated rod to the hand operated rod, or vice versa. In changing the coupling, as described above, if the notch 23 in hand operated rod 10, be not in line with the coupling finger, it is merely necessary to move this rod 10 by hand until it comes into proper alignment, the weight 34 on selector rod 33 having already biased the coupling finger 24 to press against the side of the rod 10. Thus the lever 33 is thrown over as far as it will go, and the coupling finger automatically engages in the proper notches when they are properly aligned.

The device, as described above, furnishes a ready means, all included in a single casting, for connecting up a track switch to be operated either by a power operated machine in the usual manner, or by a hand operated means also in the usual manner, and while the arrangement of switch machine, track switch, and selector and operator casing, has been shown in a particular manner in Fig. 3, it is obvious that these parts can bear other relationships to each other without in any manner changing the inventive concept.

The above rather specific description of one embodiment of the present invention is given solely for the purpose of illustration, and is not intended, in any manner whatsoever, in a limiting sense. Obviously the invention can assume many different physical forms, and is susceptible of numerous modifications, and all such forms and modifications are intended to be included within this invention, as come within the scope of the appended claims.

What it is desired to now claim, is:—

1. In a switch operator and selector, a casing, a switch rod in the casing, a second and a third rod in the casing, means comprising, a rockable finger, a lever, and a lost motion connection between the lever and finger, for coupling the switch rod with either of the other rods, and manually operable

means in the casing for operating one of said other rods.

2. In a switch operator and selector, a casing, a switch rod in the casing, a second and a third rod in the casing, means comprising a rockable finger, a lever, and a lost motion connection between the lever and finger permitting biasing the finger to either of a plurality of coupling positions at will, 10 for coupling the switch rod with either of the other rods, and manually operable means in the casing for operating one of said other rods.

3. In a switch operator and selector, a casing, a switch rod in the casing, a second and a third rod in the casing, means for coupling the switch rod with either of the other rods, manually operable means in the casing for operating one of said other rods, 20 a power operated machine for operating the other of said other rods, and means, operated by the operation of said coupling means, for controlling energization of said machine.

25 4. In a switch operator and selector, a single casing, a power operated rod in the casing, a manually operated rod in the casing, a switch rod in the casing, means to couple

the switch rod to either of the other said rods, at will, said means including a lever, 30 a cam rockable by the lever, a non-circular shaft, a locking finger slidable on the shaft, notches in the rods for receiving the finger, a drive member on the shaft having spaced arms affording a lost motion engagement with the cam, whereby to rock the shaft and finger.

5. In a switch operator and selector, a single casing, a power operated rod in the casing, a manually operable rod in the casing, a switch rod in the casing, means to couple the switch rod to either of the other said rods, at will, said means including a lever, 40 a cam rockable by the lever, a non-circular shaft, a locking finger slidable on the shaft, notches in the rods for receiving the finger, a drive member on the shaft having spaced arms affording a lost motion engagement with the cam whereby to rock the shaft and finger, a prime mover connected 45 to the power operated rod, power control means for the prime mover, and an operable connection between the power control means and said cam.

In testimony whereof I affix my signature.
WINTHROP K. HOWE.
